(57) **CLAIM**

The ornamental design for the step stool tray, as shown and described.

DESCRIPTION

FIG. 1 is a perspective rear view of the design of the present invention.

FIG. 2 is a front view of the design shown in FIG. 1.

FIG. 3 is a right side view of the design shown in FIG. 1.

FIG. 4 is a left side view of the design shown in FIG. 1.

FIG. 5 is a top view of the design shown in FIG. 1.

FIG. 6 is a bottom view of the design shown in FIG. 1; and,

FIG. 7 is a perspective rear view of the design shown in FIG. 1, illustrated with a step stool not forming part of the claimed design.

The broken lines are for illustrative purposes only and form no part of the claimed design.
